UNITED STATES PATENT OFFICE.

MARSHALL J. MATTHEWS, OF OLEAN, NEW YORK.

DESIGN FOR A CURTAIN-ROLLER BRACKET.

SPECIFICATION forming part of Design No. 21,929, dated October 25, 1892.

Application filed August 22, 1892. Serial No. 443,802. Term of patent 3½ years.

To all whom it may concern:

Be it known that I, MARSHALL J. MATTHEWS, a citizen of the United States, residing at Olean, in the county of Cattaraugus and State of New York, have invented a new and original Design for Curtain-Roller Brackets, of which the following is a specification, reference being had to the accompanying drawing, in which the figure is a side elevation of my 10 design complete.

The leading feature of my design consists in a body *a*, one side of which is straight and the other side tapering and rounded until it merges into the head *b*, which has a circular 15 outline, the straight side of the body being plain to fit against a flat surface and straight

to lie closely against the same and extending upward to and meeting the circular lines therefrom and forming the rounded and tapered spur *c*.

The head of the bracket is provided with a slotway or eye *d*.

What I claim is—

A design for a curtain-roller bracket, substantially as herein shown and described. 25

In witness whereof I have hereunto set my hand this 13th day of August, 1892.

MARSHALL J. MATTHEWS.

In presence of—

WILLIAM COLLINS,
O. A. POTTER.
